CRASH CAUSE RECORDER FOR AIRCRAFT

Sidney G. Allen, Raleigh, N. C.

Application January 30, 1937, Serial No. 123,272

4 Claims. (Cl. 116—135)

This invention relates to crash cause recorders for aircraft.

Hitherto whenever fatal aircraft crashes have occurred no positive clues have been recoverable from the wreckage to enable investigators to learn the cause of the crash and thus have an opportunity to correct faulty aircraft construction and prevent future loss of life and property.

The primary object of the present invention is to provide a recording apparatus which will only require the pilot to push a button corresponding to an indestructible legend designating the approximate cause of a crash which is imminent, unavoidable and certain to happen, to the end that such data will be available to authorized persons examining the wreckage and such probable causes of future crashes may be remedied in future construction as well as in ships in current use.

A further object of the invention is to provide recording apparatus of this type including a shield which the pilot may instantly throw over the recording plungers to prevent tampering as well as to protect the plungers against destruction by contact with wreckage.

A further object is to provide novel spring pressed locking discs corresponding to respective recording plungers, shaped and arranged so that when the hawk bill of particular plunger is pushed into locking engagement with its respective disc it will be impossible to release the plunger until the apparatus is taken apart by investigators and at the same time when one plunger is pushed all remaining plungers are positively locked against being moved so that one cause, and only one definite cause, of an impending crash may be recorded by the pilot.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a front elevation of crash cause recording apparatus constructed in accordance with the invention.

Figure 2 is a longitudinal sectional view of the apparatus taken on the line 2—2 of Figure 1 and showing one of the recording plungers in recording position.

Figure 3 is a cross sectional view taken on the

line 3—3 of Figure 1 showing the shield in released position in full lines and in operative position in dotted lines.

Figure 4 is a side elevation of the recording apparatus with portions broken away to expose the springs for forcing the shield latch into the latching groove of the cylinder.

Figure 5 is a fragmentary perspective view showing the hawk bill of one of the plungers.

Referring now to the drawing in which like characters of reference designate similar parts in the various views, 10 designates a cylinder which forms a housing for a plurality of annular locking discs 11 which are confined in axial alignment in the bore of the cylinder by cap nuts 12 and 13 which are screw threadedly engaged in the ends of the cylinder and may be sealed in position by pins 14 although other sealing means may be employed to prevent access to the discs by unauthorized persons.

The discs are mounted in the bore of the cylinder for limited movement endwise of the cylinder and are normally held stacked in contact with each other by a helical spring 15 seated in the recess of the cap nut 13 and exerting endwise pressure against the discs 11 to hold the same urged against a spacing washer 16 which abuts the mating cap nut 12, as best shown in Figure 2.

Each spring pressed annular locking disc 11 is provided in one end face with an inturned flange 17 and the peripheral edges of the disc are rounded off as shown at 18 in Figure 2 to provide a cam surface over which a respective recording plunger may pass to depress the disc against the tension of the spring 15, as will presently appear.

A plunger housing 19 is fixed to extend longitudinally of the cylinder 10 by screws 20 and pins 21, passed radially through the plunger housing and into the cylinder, or other means may be used for forming a unitary assembly of the plunger housing and the cylinder. Projecting laterally from the intersection of the cylinder and the plunger housing is a substantially rectangular panel 22, in the present embodiment of the invention the panel being interposed at one longitudinal edge between the cylinder and the plunger housing and being secured in place by the above mentioned screws 20 and pins 21. The panel is provided with attaching openings 23 for securing the apparatus to the instrument panel 40 of aircraft or in any other locality within convenient reach of the pilot.

A plurality of cylindrical recording plungers 24 equal in number to the number of spring pressed locking discs 11, are slidably mounted in annular

recesses 25 formed radially in the plunger housing 19. A helical spring 26 is sleeved on each plunger and is confined under tension in an enlarged cylindrical recess 27 one end of the spring bearing against the inner wall of the recess and the outer end of the spring bearing against a button 28 which is screw threaded onto the plunger. The spring tends constantly to hold the plunger at its outer limit of movement.

10 Each plunger is equipped with a hawk bill 29, having a base portion of substantially rectangular cross section to provide a stop shoulder 30 adapted to engage the inner face of the plunger housing 19 adjacent the opening 25 and limit outward movement of the plunger under action of its controlling spring 26. The hawk bill 29 is provided with a pointed tip forming diverging cam surfaces 31 and 32, best shown in Figure 5. These cam surfaces are adapted to force two adjoining locking discs 11 away from each other when the plunger is pushed radially inward and permit the inturned bill 33 to spring into locking engagement with the flange 17 of the respective locking disc. As best shown in Figure 2, when any 15 one of the plungers is set by the pilot in locking engagement with its respective locking disc no other plunger may thereafter be set since the discs 11 have only play enough to admit one plunger to be interleaved between the discs at 20 which time the discs are jammed against each other and against the cap nut 13 and rigid washer 16. Consequently one, and only one selected plunger can ever be moved to locking or recording 25 position.

30 By referring to Figure 1 it will be noted that legends are disposed laterally of respective ones of the plungers, such legends indicating approximate causes of crashes, such as motor failure, gas leaks, fire breaking out, lost by instrument failure or the like, and control collapse. These 35 legends are merely given by way of example as any desired legends may be used and any number of plungers and the corresponding number of locking discs may be employed as desired. All of 40 the parts are preferably formed of metal so as to be as nearly as possible indestructible and the legends are applied to the panel 20 in any suitable manner so as to be easily readable in emergencies by a pilot, and to retain as much as possible their 45 legibility after being recovered from wreckage.

50 As a precaution against tampering, and also to protect the plungers from destruction by contact with wreckage, a shield 34 is mounted to rotate about the axis of the cylinder 10 to a position shown by dotted lines in Figure 3 in which the plunger buttons 28 are embraced by the shield and usually the pilot is supposed to swing this shield to operative position instantly after depressing his selected plunger to record the cause 55 of a crash which is imminent, unavoidable, and certain to happen.

55 For rotatably mounting the shield on the cylinder a pair of bearing rings 35 are rotatably mounted on shoulders 36 formed on the cap nuts 12 and 13 and arcuate supporting arms 37 are riveted to the rings as shown at 38 or otherwise secured in place. The arcuate arms are bridged by a bar 39 which is integral with the shield 34, as best shown in Figure 3, and is provided with housings 70 40 in which helical springs 41 are disposed. These helical springs 41 bear upon one flange of a channeled latch member 42 which is slidably mounted on the underneath face of the bar 39, and hold said flange in frictional engagement with the cylindrical wall of the cylinder 10. During rota-

tion of the shield on its axis to a position to embrace and protect the plungers, the springs 41 will force said flange of the latch into a latching groove 43 formed longitudinally in the wall of the cylinder so that the shield is yieldably held in its operative position and cannot be removed from operative position until the mating flange 44 of the latch is manually pulled outwardly to release the latching flange from the latching groove.

10 In operation the apparatus may be mounted on any suitable part of the aircraft within convenient reach of a pilot. The shield 34 is normally rocked to released position to expose the plunger buttons 28, in which position inturned stop fingers 45, best 15 shown in Figure 4, on the arcuate arms 37, are in position to engage the rear face of the panel 22 and prevent swinging of the shield out of convenient reach of the pilot. In the event of an accident involving any failures such as are indicated 20 by the legends on the panel 22, at the moment the pilot decides that a crash is imminent, unavoidable, and certain to happen, he may record the defect by quickly pushing in the corresponding plunger and then instantly rotating the shield 25 24 into position over the row of plungers. As previously explained, the selected plunger will interlock with its respective locking disc and cannot be dislodged until authorized persons, investigating the cause of the crash, remove the sealed cap 30 nuts 12 and 13 to permit the spring 15 to release the locking discs. Thus investigators seeking the cause of a crash may have a clue, recoverable from the wreckage, as to the cause of the crash, as pointed out by the pilot, and thus have an opportunity 35 to correct faulty aircraft construction and prevent future loss of life and property in future aircraft construction as well as current aircraft in daily use.

40 From the above description it is thought that the construction and operation of the invention will be fully understood without further explanation.

What is claimed is:

1. A crash cause recorder for aircraft comprising a supporting cylinder, means for securing the cylinder to aircraft within convenient reach of a pilot, spring pressed recording plungers, distinctive legends associated with respective plungers designating probable causes of a crash, and a plurality of locking discs carried 45 by the cylinder and corresponding to respective plungers, the discs being so shaped and arranged that when a selected plunger is set in locking engagement with its respective disc by a pilot 50 it will be impossible to release the set plunger or to operate any of the remaining plungers.

2. A crash cause recorder for aircraft comprising a supporting cylinder, means for securing the cylinder to aircraft within convenient reach of a pilot, spring pressed recording plungers adapted to be selectively operated by a pilot 60 when a crash is imminent, unavoidable, and certain to happen, distinctive legends associated with respective plungers designating probable causes of a crash, a plurality of locking discs carried by the cylinder and engageable by and in alignment with respective recording plungers, and a spring controlling the discs to permit sufficient play between the discs to admit only 65 the one selected plunger to be interleaved between the discs when a selected plunger is set by the pilot in locking engagement with its respective disc and prevent setting of any of the remaining plungers.

3. A crash cause recorder for aircraft comprising a supporting cylinder, cap nuts closing the ends of the cylinder, means for securing the cylinder to the aircraft within convenient reach 5 of a pilot, a plunger housing extending longitudinally of one side of the cylinder, plungers carried by the housing and adapted to project into the cylinder, a plurality of locking discs nested in the cylinder between the cap nuts, 10 and a compression spring in the cylinder urging the discs endwise, each disc having a locking flange and each plunger having a hawk bill extremity engageable with said flange, said hawk bill being beveled to provide cam faces adapted 15 to enter between and move apart two adjoining discs whereby the hawk bill of a selected set plunger will lockingly engage the flange of a respective locking disc, said spring permitting predetermined play between the discs so that 20 when a selected plunger is set by the pilot in locking engagement with its respective disc it

will be impossible to release the set plunger or to operate any of the remaining plungers.

4. A crash cause recorder for aircraft comprising a supporting cylinder, means for securing the cylinder to aircraft within convenient reach of a pilot, a plurality of recording plungers arranged on one side of the cylinder and projecting into the cylinder, locking discs in the cylinder adapted to be selectively engaged by respective plungers when a predetermined 10 plunger is set by a pilot, legends associated with the plungers designating probable causes of a crash, a shield mounted for rotation on the axis of the cylinder and adapted to embrace said plungers and protect the plungers from injury 15 by contact with wreckage, and means for releasably locking the shield to the cylinder, said shield being adapted to be rotated to embrace the plungers by the pilot after setting of a selected plunger. 20
